US0D1047784S

(12) **United States Design Patent** (10) Patent No.: **US D1,047,784 S**
(45) Date of Patent: ** Oct. 22, 2024

(54) **ROLLATOR**

(71) Applicant: **Eliana Delatorre**, East Walpole, MA (US)

(72) Inventor: **Eliana Delatorre**, East Walpole, MA (US)

(**) Term: **15 Years**

(21) Appl. No.: **29/931,337**

(22) Filed: **Mar. 6, 2024**

(51) LOC (14) Cl. **12-12**

(52) U.S. Cl.

USPC **D12/130**

(57) **CLAIM**

The ornamental design for a rollator, as shown and described.

DESCRIPTION

FIG. 1 is a top front perspective view of a rollator, showing my new design;

FIG. 2 is a left-side elevation view thereof, the right-side elevation view being a mirror image thereof;

FIG. 3 is a front elevation view thereof;

FIG. 4 is a rear elevation view thereof;

FIG. 5 is a top plan view thereof; and,

FIG. 6 is a bottom plan view thereof.

The evenly spaced broken lines shown in the drawings depict portions of the rollator that form no part of the claimed design.

1 Claim, 4 Drawing Sheets
